Primary Examiner — Elizabeth J Oswecki(74) Attorney, Agent, or Firm — Nitin Kaushik(57) CLAIM

The ornamental design for a pistol safe, as shown and described.

DESCRIPTION

FIG. 1 is a front, bottom, and right side perspective view of a pistol safe, showing my new design in an open position;

FIG. 2 is a front, bottom, and right side perspective view thereof, shown in a closed position;

FIG. 3 is a front, top and left side perspective view thereof;

FIG. 4 is a front view thereof;

FIG. 5 is a rear view thereof;

FIG. 6 is a left side view thereof;

FIG. 7 is a right side view thereof;

FIG. 8 is a top view thereof;

FIG. 9 is a bottom view thereof;

FIG. 10 is an enlarged portion view taken from encircled portion labeled, "10," in FIG. 1;

FIG. 11 is an enlarged portion view taken from encircled portion labeled, "11," in FIG. 1; and,

FIG. 12 is an enlarged portion view taken from encircled portion labeled, "12," in FIG. 1.

The even dashed broken lines represent unclaimed environment and form no part of the claimed design. The dash-dot lines represent the boundaries of the enlarged portion views of FIGS. 10-12 shown in FIGS. 1, and 10-12 and form no part of the claimed design.

1 Claim, 12 Drawing Sheets(56)
